UNITED STATES PATENT OFFICE.

JOHN I. PENNINGTON, OF BALTIMORE, MARYLAND.

SAFETY-RECEPTACLE FOR MERCHANDISE.

1,110,816.

Specification of Letters Patent. Patented Sept. 15, 1914.

Application filed March 12, 1914. Serial No. 824,131.

To all whom it may concern:

Be it known that I, JOHN I. PENNINGTON, a citizen of the United States, residing at Baltimore, in the State of Maryland, have 5 invented certain new and useful Improvements in Safety-Receptacles for Merchandise; and I do hereby declare the following to be a full, clear, and exact description of the invention, such as will enable others skilled in the art to which it appertains to 10 make and use the same.

My invention relates to receptacles for receiving and temporarily storing articles of domestic merchandise such as cream, milk, bread, grocers' packages, mail and the like, 15 has for its object the prevention of pilfering, petty thieving and contamination from cats and dogs, by depositing containers and packages in a receptacle accessible to dairy-men, delivery-men and postmen, and capable of being opened only by the occupant of the premises without the use of a key by either party to the transaction.

The invention consists in such a receptacle, which will be fully disclosed in the following specification and claim.

In the accompanying drawings, which form part of this specification:—Figure 1 is a perspective showing the receptacle in position on a door jamb in position to receive merchandise. Fig. 2 is a horizontal section on an enlarged scale, showing the door open, the receptacle capable of being moved toward the door and in position to be detached from the jamb. Fig. 3 is an elevation partly in section, showing the locking mechanism. Fig. 4 is a front view of part of the locking mechanism detached from the door, and Fig. 5 is a like view showing the latch engaged 35 by the keeper on the door.

Reference being had to the drawings and the designating characters thereon, the numeral 1 indicates a conventional door-jamb, 2 a door and 3 the receptacle detachably secured to the door-jamb, but which 45 cannot be removed or detached from the jamb so long as the door remains closed.

In the back 3' of the receptacle is a horizontally arranged slot 4 enlarged at one end 50 to pass over the head of a screw 5 and on which screw the receptacle is supported and moved laterally, as shown in Fig. 2, to release the receptacle from the jamb.

6 indicates a gravity-latch, preferably 55 having a long arm which is provided with a

projection or catch 7 at its free end, and a short arm 8 to which a chain 9 or a piece of cord is attached, which extends through the back 3' of the receptacle and provides a ready means for disengaging the lever from 60 a hasp and releasing the door so that the contents may be removed.

10 indicates a housing in which the latch is supported on a pin 11, and the long arm extends through a vertical slot 12 in the front 65 wall of the housing to limit its vertical and lateral movement. The housing is provided with flanges 13 by which it is secured to the side of the receptacle.

14 indicates a member having a vertical 70 wall 15 which is engaged by the arm 6, and an elongated or rectangular groove 16 in which a combined trip and keeper 17 operates. The part 17 is attached to or forms an integral part of a rod 18 which extends 75 through and is supported at its inner end in the wall of the member 14 15, and the rod extends through the door 19 of the receptacle and is provided with suitable means such as a knob 20, or the like for operating 80 the part 17. On the inner end of the rod 18 is a spiral spring 21, secured at one end in said rod, wound spirally thereon, and the opposite end of the spring secured to the member 14 to exert tension on the part 85 17 to return it to its seat in the groove 16 and to exert pressure thereon when it is performing the office of a keeper.

The operation is as follows: The receptacle is placed on the door-jamb, suspended 90 on the screw 5 and pushed toward the door 2 with the part 17 lying in the groove 16, when the door 19 of the receptacle is closed and latched, but not locked.

The dairy-man or other delivery man can 95 then open the door and place an article of merchandise in the receptacle. He then raises the part 17, and closes the door, 19 when the part 17 will rest upon the end of the latch 6 and hold the latch 7 in engagement with the wall 15 so that the door of the receptacle cannot be opened. To open 100 the door 19 of the receptacle, the door 2 must first be opened as shown in Fig. 2, the receptacle moved toward the door by 105 sliding on the screw 5 until the chain or cord 9 reaches the rabbet in the door-jamb when the latch 6 is raised out of engagement with the flange 15, when the door 19 may 110 be opened and the article in the receptacle

removed, or the receptacle 3 may be detached from the door-jamb.

From the foregoing description, it is apparent that the door of the receptacle having been closed with the keeper 17 resting upon the inner end of the lever 6, the door cannot be opened without first opening the door 2 which leads to an apartment or other dwelling and the contents of the receptacle are safe.

The receptacle may be made of any suitable material and of different dimensions to suit the uses to which it may be applied.

It is obvious that changes in details of construction may be made without departing from the spirit of my invention.

Having thus fully described my invention, what I claim is:

A receptacle provided with a gravity latch pivotally secured thereto, a housing 20 in its wall through which one arm of said latch extends, a member on the door of the receptacle engaged by said latch and having a member constructed to raise the latch, and 25 also to secure it in engagement with the first member, and a member engaging the opposite end of the latch and extending through the wall of the receptacle to disengage the latch.

In testimony whereof I affix my signature in presence of two witnesses.

JOHN I. PENNINGTON.

Witnesses:

EDWIN R. DOWNES,

DANIEL RILEY.
